H. G. PIETZ,
PITCHFORK ATTACHMENT,
APPLICATION FILED APR. 18, 1916.

1,245,162.

Patented Nov. 6, 1917.

UNITED STATES PATENT OFFICE.

HENRY G. PIETZ, OF TRIPP, SOUTH DAKOTA.

PITCHFORK ATTACHMENT.

1,245,162.

Specification of Letters Patent. Patented Nov. 6, 1917.

Application filed April 18, 1916. Serial No. 91,893.

To all whom it may concern:

Be it known that I, HENRY G. PIETZ, a citizen of the United States, residing at Tripp, in the county of Hutchinson and 5 State of South Dakota, have invented certain new and useful Improvements in Pitchfork Attachments, of which the following is a specification.

My invention relates to improvements in 10 means for securing the fork of a pitch fork or like implement to its handle.

An important object of the invention is to provide means of the above mentioned character, which are simple in construction, inexpensive to manufacture, strong and durable.

Other objects and advantages of the invention will be apparent during the course of the following description.

20 In the accompanying drawings forming a part of this specification and in which like numerals are employed to designate like parts throughout the same,

Figure 1 is a perspective view of a pitch 25 fork embodying my invention,

Fig. 2 is a perspective view of a fork or implement holding member,

Fig. 3 is a central longitudinal view through the socket of the fork and associated 30 elements, and,

Fig. 4 is a similar view through the rear end of the handle, showing adjusting means.

In the drawings, wherein for the purpose of illustration is shown a preferred embodiment of my invention, the numeral 5 designates a fork, of any well known or preferred construction, or like implement, formed upon or carried by a socket 6, which is preferably integral therewith. This socket is 40 adapted for the reception of the reduced forward end of a handle 7, as shown.

The numeral 8 designates a holding member, having one end bent in the form of a hook or loop 9, straddling a portion of the 45 fork 5, between the tines thereof, as shown. The holding member 8 has its body portion apertured as shown at 10, for the reception of the bent end of the wire or rod 11, which end is secured within the aperture by a head 50 12, formed by the wire being flattened at this point. The wire extends longitudinally of the handle 7 and is held against displacement by a staple 13, which is secured to the handle. The handle 7 is provided near its 55 rear end with a longitudinally extending

opening 14, passing through the rear end thereof and leading to the surface of the handle, at a point arranged near and spaced a substantial distance from the rear end of the handle. The wire or rod 11 passes 60 through the opening 14 and its free end is screw-threaded, for engagement with an adjusting nut 15, contacting with a metallic cap 16, carried by the rear end of the handle 7.

From the foregoing description, it is obvious that the member 8 will hold the socket 6 upon the reduced end of the handle 7, and the binding action of the member 8 may be regulated by manipulation of the nut 15. 70 When it is desired to remove the fork 5 from its handle, the nut 15 is unscrewed from the wire 11 and such wire moved longitudinally sufficiently to permit of the member 8 disengaging the fork 5, at which 75 time the fork may be removed from the handle.

It is to be understood that the form of my invention herewith shown and described is to be taken as a preferred example of the 80 same, and that various changes in the shape, size, and arrangement of parts may be resorted to without departing from the spirit of the invention or the scope of the subjoined claim.

Having thus described the invention, I claim:

A device of the character described comprising a handle having an opening formed in its rear end and extending longitudinally 90 thereof for a substantial distance with the forward portion of the opening projecting upwardly and passing through the surface of the handle, said handle having its forward end tapered; a socket member to fit 95 upon the tapered end of the handle; a ground treating implement formed integral with the socket member; a holding member having its forward end formed substantially as wide as the space between portions of the ground treating implement and bent into a hook for receiving a portion of the implement and adapted to engage and draw the implement and socket toward the rear end of the handle, said holding member having an opening formed in its rear end; a wire extending longitudinally of the handle and having one end bent at a right angle to extend within the opening formed 105 in the holding member and flattened to pro- 110

vide a head for insuring a positive connection between the wire and the holding member, the rear end of the wire extending through the opening and beyond the rear end of the handle and provided with screw-threads; a nut to engage the screw-threaded end of the wire to adjust the same longitudinally of the handle; and a staple engag-

ing the wire to prevent displacement laterally of the handle.

In testimony whereof I affix my signature in presence of two witnesses.

HENRY G. PIETZ.

Witnesses:

GEORGE G. PIETZ,

HENRY KLATT, Jr.
